UNITED STATES PATENT OFFICE.

JOHN HANLON, OF NEW YORK, N. Y., ASSIGNOR TO WILLIAM W. GIBBS,
OF SAME PLACE.

GAS APPARATUS.

SPECIFICATION forming part of Letters Patent No. 254,213, dated February 28, 1882.

Application filed July 19, 1881. (No model.)

To all whom it may concern:

Be it known that I, JOHN HANLON, of the city and State of New York, have invented certain new and useful Improvements in Gas Apparatus, of which the following is a clear, full, and exact description, reference being had to the accompanying drawings, making part of this specification, in which—

Figure 1 is an elevation, partially in section, of a condenser. Fig. 2 is a cross-section through the same. Fig. 3 is a cross-section of a purifier. Fig. 4 is a detached perspective view of the liquid seals for the cut off, with suitable elastic packing.

15 The object of my present invention is the condensing and purifying of illuminating-gas; and it consists in the several combinations of devices hereinafter explained and claimed.

In order that those skilled in the art may 20 make and use my invention, I will proceed to describe the manner in which I have carried it out.

In the said drawings, the condenser F is composed of a series of vertical cylinders, f, surrounded by a water jacket, g, through which 25 there is a constant flow of water by means of the pipes H, the cold water passing in through the lower pipe and out through the upper pipe after becoming heated. Each water jacket 30 communicates with each pipe by means of proper openings, thus allowing each jacket to receive its water directly and discharge the same. I provide each condensing-cylinder at its top with a combined elastic and water packing to insure a tight joint, which is essential. 35 To this end I construct around the head of each cylinder a cup, in the bottom of which is snugly fitted an elastic annulus of suitable material, and the cup is then partially filled with a liquid to receive the dip-rim of the cylinder- 40 cap. This forms a compound seal, which secures the gas against the possibility of escape through the top of the cylinder. Each cylinder is provided with a central vertical diaphragm, which causes the gas to pass up one side of each cylinder to the top, and again down on the other side of the diaphragm, and so on through the whole condenser. The lower 45 portions of the cylinders rest in a liquid seal of any ordinary construction.

The purifier is of the usual construction,

with two compartments supplied with the customary purifying materials. Below this purifier I place the longitudinal central crank-shaft, J, as shown in Fig. 4, to operate the liquid seals i, whereby the compartments are alternately cut off or opened by a single slight turn of the shaft J. The liquid seals i are loosely journaled in bearings formed on the cross-arms K, and by this construction the liquid is allowed to retain at all times a level sealing-surface. In the bottom of the sealing-cups i, and below the liquid, I place a thin sheet of suitable elastic packing to guard against the evaporation of the water seal, thus forming in each cup a compound seal.

I am aware that a water seal in gas-purifiers is not broadly new, nor do I claim such as my invention.

Having thus described my invention, what 70 I claim as new, and desire to secure by Letters Patent, is—

1. The condenser F, composed of a series of vertical cylinders, surrounded with water jackets and provided with diaphragms, in combination with a cold-water pipe connecting directly with each jacket and a discharge-pipe similarly connected, substantially as and for the purpose described.

2. The cylinders f, having the cups g, provided with a rubber packing and water seal, in combination with the cylinder-cap provided with a dip-rim, substantially as and for the purpose described.

3. The purifier I, in combination with the 85 central crank-shaft, J, and the seals i, connected therewith, whereby the compartments are cut off or opened, substantially as described.

4. The central shaft, J, provided with the cross-arms K, in combination with the journaled seals i, substantially as and for the purpose set forth.

5. The seals i, provided at their bottoms with a thin sheet of elastic packing, and on that a liquid seal, in combination with the dip-pipes of the purifier, substantially as described.

JOHN HANLON.
